Patented Jan. 7, 1969

213,108

VIDEOTELEPHONE TRANSCEIVER

Henry Dreyfuss, South Pasadena, Calif., and Rembert R. Stokes, Middletown, N.J., assignors to Bell Telephone Laboratories, Incorporated, Murray Hill, N.J., a corporation of New York

Filed Nov. 24, 1967, Ser. No. 9,548

Term of patent 14 years

U.S. Cl. D26—14
Int. Cl. D14—03

FIG. 1

FIG. 2

FIG. 3

FIG. 4

FIG. 1 is a right front perspective view of a first embodiment of a videophone transceiver showing our new design;

FIG. 2 is a left rear perspective view of the videophone transceiver shown in FIG. 1;

FIG. 3 is a right front perspective view of a second embodiment of a videophone transceiver showing our new design; and

FIG. 4 is a right rear perspective view of the videophone transceiver shown in FIG. 3.

We claim:

The design for a videophone transceiver, substantially as shown and described.
